UNITED STATES PATENT OFFICE

LOUIS E. WARD, OF MIDLAND, MICHIGAN, ASSIGNOR TO THE DOW CHEMICAL COMPANY,
OF MIDLAND, MICHIGAN, A CORPORATION OF MICHIGAN

ELECTROLYTIC CELL CURTAIN

Application filed June 10, 1929. Serial No. 369,683.

This invention relates in general to a curtain-like means for separating anodic from cathodic products of electrolysis. It relates specifically to a sectional type of curtain adapted for use in separating metallic magnesium and chlorine gas produced by the electrolysis of a fused saline bath containing magnesium chloride.

Owing to the high temperature to which such a curtain is exposed, the corrosive action of chlorine and other anodic products and further to the fluxing or erosive action of the fluid hot metal upon ceramic ware, in general, and still further to the necessity that the curtain have electrical non-conductive property, the choice of material for such a curtain is somewhat narrow and the details of construction require careful design. Refractory material such as fire-clay or brick shapes is customarily employed and because such material suffers erosion, corrosion, or breakage it is essential that the details of design shall permit the easy substitution of new parts to replace those no longer serviceable. It may be stated, in general, that such pieces of large size are relatively more expensive than those of small size, are more difficult to pack, ship, unpack, and store without breakage and are more readily broken when handled in a replacement operation. Small pieces, on the contrary, are more cheaply made, more easily packed and transported, easily stored in small space, and can be handled with a minimum of breakage and loss.

I have invented a curtain composed of a plurality of suitably shaped plates of simple design and small size including means to support said plates in the cell permitting the easy removal and replacement of any single piece even without suspending operation of the cell during such repairs.

To the accomplishment of the foregoing and related ends, the invention, then, consists of the parts and assembled structure herein-after fully described and particularly pointed out in the claims, the annexed drawings and the following description setting forth in detail certain forms of the invention, such disclosed forms illustrating, however, but some

of the various ways in which the principle of the invention may be used.

In said annexed drawings:

Fig. 1 is a vertical cross section through an electrolytic cell adapted to the electrolysis of a fused bath, such as one containing magnesium chloride for the production of magnesium metal and chlorine. Fig. 2 is a top plan view of the rectangular shaped sectional curtain shown in Fig. 1. Fig. 3 is a vertical cross section on A—B of Fig. 2 at right angles to that of Fig. 1 showing the same rectangular sectional curtain and details of support for the same. Fig. 4 is a part plan view of a circular sectional curtain. Fig. 5 is a part plan view of another circular curtain. Fig. 6 is a side view of one of the hooked bricks employed in Figs. 1, 2, and 3 as supports for the curtain plates. Fig. 7 is an edge view and Fig. 8 a side view of a segment of the curtain in Fig. 2. Fig. 9 is an edge view and Fig. 10 a side view of another form of segment or plate member of a curtain. Figs. 11 and 12 show a variety of forms of sectional curtain plates and supports for same. Fig. 13 shows a still further variation in a curtain support. Fig. 14 shows in a horizontal cross section through a curtain a modification in form involving overlapping of one section upon another. Fig. 15 is a similar cross section showing a corrugated form of sectional curtain. Fig. 16 is a plan view of a hooked brick support for sections or plates of a circular or curved curtain. Fig. 17 is a part plan view of a circular curtain including the brick shown in Fig. 16.

My curtain may take a wide variety of forms employing also a like variety of forms of support and may, in general, be applied to a variety of electrolytic cell constructions. I will describe it as applied to the cell construction indicated in Fig. 1.

Referring to Fig. 1, 1 is a cathode cell pot set in a furnace adapted to supply initial or control heat for the bath. 2 is an anode, a number of which may be set in line as indicated in the plan Fig. 2 and the corresponding cross section Fig. 3. Such anodes depend in the bath from above being preferably supported from adjustable hangers permitting

motion in a vertical direction, removal from the bath, reinsertion therein and for varying the depth of dipping in the bath.

In the type of cell illustrated, the pot is provided with an inverted trough 3, adapted to trap liberated metal rising from the active cathode surface 4 of pot 1. Such metal is shown at 5. A provision may be advisedly made to lead such trapped metal to a collecting or gathering zone or well for easy access and removal. The curtain 6, preferably composed of refractory plates, is hung from a series of bricks 7 composing a part of the superstructure of the setting. The curtain 6 will be composed of a plurality of plate-like pieces arranged in juxtaposition edge to edge to form an enclosure about the anode or about a plurality of anodes as the case may be. Cover slabs 8 resting upon suitably disposed brick work of the superstructure inclose a space 9 into which the chlorine gas or other gaseous products are directed by the sleeve-like flue formed by the curtain. The curtain not only serves as a means of separating the anodic gas from the metal, but it also covers those portions of the pot surface from which liberated metal may not directly enter the collecting trap, thereby restricting the liberation of the metal thereon to a minimum whereby incidental losses are reduced. In the particular cell illustrated, the bath level will be at or about 10 and a clearance space will be desirably left between the faces of the trap 3 and the curtain to permit the small amount of metal liberated on the outer faces of the trap to rise freely to the surface of the bath, whereby it will be removed from immediate contact with the lower portions of the curtain. Provision may be made as understood in the art to remove such floating metal from the surface of the bath in the compartment 11, as by skimming or causing the metal to float to a collecting zone, so as to avoid its erosive action upon the curtain.

It will be seen from Fig. 2, which is a plan of the curtain of the cell shown in Fig. 1 and employing four anodes in a row, that the curtain plates 6 form continuous rows along two sides of the rectangle inclosed by the curtain and the end plates 6' close the ends of the rectangle. Various methods of supporting the curtain plates may be employed a number of which will be described hereinafter.

Fig. 4 is a part plan view of a circular or ring shaped curtain, here shown, composed of plates indicated at 6, 6', 6'', 6''' and 6'''. The support for these plates is shown in Figs. 9 and 16. Fig. 5 is a part plan of another circular curtain showing as in Fig. 4 a variety of forms of plates, either flat, curved, lapped or merely butted. Fig. 6 is an edge view of a hooked brick showing, in general, one form of support for the curtain plates.

Figs. 9, 10 and 17 are vertical cross sections, face and plan views of plates and supports for a circular curtain showing, in general, a form of plate and support. Fig. 16 shows the hooked brick of Fig. 9 in plan. Such brick is provided with a sloping peg-like projection onto which the curtain may be slipped to engage suitable notches or holes therein. Such peg-like projections and the notches in the plates may have a variety of forms, a number of which are indicated in face view in Figs. 11 and 12. The forms of notches shown in Fig. 11 are adapted to the side edges of the individual curtain plates, whereas those shown in Fig. 12 are adapted to the upper interior or edge portion of the plate rather than to the side edges thereof.

I provide as described, the individual curtain plates with a suitably notched, hooked, or otherwise shaped contour adapted to engage with projections upon fixed portions of the superstructure of the cell. Such projections are adapted to match the contour of the curtain plates in a manner not only to support same in a vertical direction but to retain the slab in position against small forces tending to push it off the support.

I find it preferable to have the peg-like supports slope as indicated or to provide them with a notch shaped form as shown in Fig. 13 in which the peg 12 has an upward projection at the outer end and the plate 6 has a corresponding downward projection in the notch enabling the hook to retain the plate. Many other equivalent forms of curtain plate supporting pegs or the like might be shown.

Referring to Figs. 11 and 12, ears 13 may be provided, pierced with holes, or other equivalent tabs or lugs may be added to the plate suited to enable the easy grasping of a hot plate with such a tool as will permit handling it for removal and replacement in a hot cell under operation. A hole, 15, adapted for the insertion of a handling hook is shown in Fig. 8 and two such are shown in Fig. 3. The abutting edges of the plate may obviously have various angular relations to the plate faces. A corner of a curtain may be turned in a variety of ways, one of which is shown in Fig. 2. Alternative ways of turning a corner such as in Fig. 2 may use a longer supporting peg, projecting beyond the face of the plate 6, and the plate 6' will be carried on the portion of the peg projecting beyond the face of plate 6. Many such forms are obvious.

I construct or assemble my curtain by first laying up suitable supporting members in the relatively fixed superstructure of the cell in relation one to another such as to form a plurality of correctly placed supports for the curtain members. I then hang the curtain members from the supports so provided, one at a time or several or all at a time, as may

be convenient, adjusting same to positions in juxtaposition each to its adjacent member to form a partition or curtain dipping in the bath between the surface areas of the bath 5 through or from which the anodic and cathodic products of electrolysis pass on their way out of the bath.

When it becomes necessary for any reason to substitute a new plate for one in service, 10 I provide such plate in a handy location to the cell, preferably preheated to the temperature of the bath, so as to avoid cracking when placed in position. I then remove such portion of the cover slab 8 as will enable access 15 to the curtain at the location requiring repair without interrupting the operation of the cell. I insert a suitable tool, remove the damaged plate and thereupon replace it with the fresh preheated one. The manipulation will, of 20 course, depend upon the character of the support and the like character of the engaging contour of the plate but, in general, the fresh plate will be lowered into place, slipped onto the hook and there adjusted in position in 25 alignment with the adjacent plates. I thereupon replace the cover slab. In order to avoid escape of anodic gas into the room enough suction will be carried upon the conduit 4, in Fig. 1, through which the anodic products are withdrawn, to draw a current 30 of air into the cell through the opening made by removing the cover slab during repair operations.

My invention is applicable to advantageous use in both large and small scale operation. It is particularly applicable in large scale operations employing a plurality of anodes in a large cell. A sectional curtain for such a cell may be readily constructed of small 35 pieces or plates of the character described to form a rectangular, oval, circular, or other enclosure or partition for leading the anodic gas to the outlet, for covering exposed portions of the pot upon which it is desired to 40 restrict cathodic action, and for separating the floating metal from the anodic products. Such a curtain may be constructed far more cheaply and safely than a large sized single piece curtain and renewals will be confined to 45 the replacement of small pieces for any one breakage whereas when large single piece curtains are used, breakage at a single point will 50 require the substitution of a new piece of large size and cost. Not only are small refractory pieces more cheaply made than large 55 ones but they suffer less breakage in drying, burning, packing, shipping, and storage. They require less boxing and packing materials for shipment, less storage room and less 60 labor in handling, and are in many respects highly advantageous relative to large sized pieces. I have found the disadvantage incident to the discontinuous character of the curtain, due to the more or less imperfect joint 65 obtainable in actual practice between the ad-

joining plate edges, to present no serious difficulties in operation. It is customary to employ a suction upon the anodic gas chamber of the cell which effectually prevents issue of the chlorine through the joints in the curtain, and such joints are sufficiently close in practice to substantially prevent metal from passing into the anodic compartment from without. In the form of cell construction illustrated in Fig. 1, the bulk of the metal liberated is trapped as indicated, and but a small portion is liberated upon the surfaces of the metal adjacent to the curtain to become later liable to passage in part through the curtain joints into the anodic gas chamber before removal as metal product.

I have described my invention employing refractory material for the curtain plates. Other materials are, however, available such as ceramic materials, sintered or fused magnesia, alumina or the like, resistant to the particular bath employed, and I conceive my invention as covering the use of any suitable refractory material for a sectional curtain.

Other modes of applying the principle of my invention may be employed instead of the one explained, change being made as regards the means and steps herein disclosed, provided those stated by any of the following claims or the equivalent be employed.

I therefore particularly point out and distinctly claim as my invention:—

1. In apparatus of the character described, a plate-like curtain member of refractory material adapted to engage a horizontally disposed member of the cell superstructure so as to be suspended vertically therefrom, and capable of being assembled edge to edge with other like plates to form a continuous sectional partition wall or curtain.

2. In apparatus of the character described, a plate-like curtain member of refractory material adapted to engage a peg-like extension projecting laterally from a horizontal cover member and thereby being suspended vertically therefrom, and capable of being assembled edge to edge with other like plates to form a continuous sectional partition wall or curtain.

3. In apparatus of the character described, a plate-like curtain member of refractory material having a notched contour adapted to engage a peg-like extension projecting laterally from a horizontal cover member and being thereby suspended vertically therefrom, and capable of being assembled edge to edge with other like plates to form a continuous sectional partition wall or curtain.

4. In apparatus of the character described, a sectional curtain comprising a plurality of plate-like members of refractory material adapted to engage with horizontal members of the cell superstructure so as to be suspended vertically edge to edge therefrom and held

in place thereby to form a laterally bounded enclosure.

5. In apparatus of the character described, a sectional curtain comprising a plurality of plate-like members of refractory material adapted to engage with peg-like extensions projecting laterally from horizontal cover members, being vertically suspended edge to edge therefrom and held in place thereby to 10 form a laterally bounded enclosure.

6. In apparatus of the character described, a sectional curtain comprising a plurality of plate-like members of refractory material having a notched contour adapted to engage 15 with peg-like extensions projecting laterally from horizontal cover members, being suspended vertically edge to edge therefrom and held in place thereby to form a laterally bounded enclosure.

20 7. In an apparatus for the electrolysis of a fused salt bath, the combination of a vessel to contain such bath, an anode depending centrally in said bath, horizontally disposed cover members supported upon the rim of said vessel and extending inwardly to cover the outer part of the bath surface while leaving a central opening surrounding and spaced away from said anode, a plurality of plate-like members of refractory material suspended edge to edge from said cover members within said opening to form a continuous sectional curtain circumscribing said anode and dipping below the surface of said bath.

35 8. In an apparatus for the electrolysis of a fused salt bath, the combination of a vessel to contain such bath, an anode depending centrally in said bath, horizontally disposed cover members supported upon the rim of said vessel and extending inwardly to cover the outer part of the bath surface while leaving a central opening surrounding and spaced away from said anode, said cover members being provided with peg-like extensions projecting laterally within said opening, a plurality of plate-like members of refractory material adapted to engage said pegs and suspended therefrom edge to edge forming a continuous sectional curtain circumscribing said anode and dipping below the surface of 50 said bath.

9. In an apparatus for the electrolysis of a fused salt bath, the combination of a vessel to contain such bath, an anode depending centrally in said bath, horizontally disposed cover members supported upon the rim of said vessel and extending inwardly to cover the outer part of the bath surface while leaving a central opening surrounding and 55 spaced away from said anode, said cover members being provided with peg-like extensions projecting laterally within said opening, a plurality of plate-like members of refractory material having a notched contour 60 adapted to engage said pegs and suspended 65

therefrom edge to edge to form a continuous sectional curtain circumscribing said anode and dipping below the surface of said bath.

10. In an apparatus for the electrolysis of a fused salt bath, the combination of a vessel 70 to contain such bath, a plurality of anodes depending centrally in said bath, horizontally disposed cover members supported upon the rim of said vessel and extending inwardly to cover the outer part of the bath surface while leaving a central opening surrounding and spaced away from said anodes, a plurality of plate-like members of refractory material suspended edge to edge from 75 said cover members within said opening to form a continuous sectional curtain circumscribing said anodes and dipping below the surface of said bath.

11. In an apparatus for the electrolysis of a fused salt bath, the combination of a vessel 80 to contain such bath, a plurality of anodes depending centrally therein, horizontally disposed cover members supported upon the rim of said vessel and extending inwardly to cover the outer part of the bath surface while leaving a central opening surrounding and spaced away from said anodes, said cover members being provided with peg-like extensions projecting laterally within said opening, a plurality of plate-like members 85 of refractory material adapted to engage said pegs and suspended therefrom edge to edge to form a continuous sectional curtain circumscribing said anodes and dipping below the surface of said bath.

12. In an apparatus for the electrolysis of a fused salt bath, the combination of a vessel 90 to contain such bath, a plurality of anodes depending centrally therein, horizontally disposed cover members supported upon the 105 rim of said vessel and extending inwardly to cover the outer part of the bath surface while leaving a central opening surrounding and spaced away from said anodes, said cover members being provided with peg-like extensions projecting laterally within said opening, a plurality of plate-like members of refractory material having a notched contour 110 adapted to engage said pegs and suspended therefrom edge to edge to form a continuous sectional curtain circumscribing said anodes and dipping below the surface of said bath.

Signed by me this 8th day of June, 1929.
LOUIS E. WARD.
